CLAIM

The ornamental design for a softspeaker cover, as shown in the accompanying drawings.

DESCRIPTION

FIG. 1 is a perspective 3D view of the softspeaker cover showing our new design;

FIG. 2 is a front view of the softspeaker cover;

FIG. 3 is a rear view of the softspeaker cover;

FIG. 4 is a right side elevational view of the softspeaker cover, the left side being a mirror image thereto;

FIG. 5 is a top plan view of the softspeaker cover; and,

FIG. 6 is a bottom plan view of the softspeaker cover.
